UNITED STATES PATENT OFFICE.

HARRY N. HALL, OF ALBANY, GEORGIA.

ROAD-BUILDING MACHINE.

1,185,090.

Specification of Letters Patent. Patented May 30, 1916.

Application filed December 3, 1915. Serial No. 64,889.

To all whom it may concern:

Be it known that I, HARRY N. HALL, a citizen of the United States, residing at Albany, Dougherty county, State of Georgia, have 5 invented certain new and useful Improvements in Road-Building Machines, of which the following is a specification.

This invention relates to road building machines and more particularly to road 10 drags and similar machines which may be used for the purpose of scraping or grading roads.

The principal object of the invention is to improve machines of the above character 15 and provide a machine thoroughly adapted to its work and one which is flexible and easy of control.

Another object of the invention is to provide a machine of this character in which 20 the blades are rigidly mounted and arranged so as to be given a substantially straight motion under practically all conditions so as to keep them from scooping or otherwise doing imperfect work on very wet 25 or on hard and rocky roadways.

Another feature of improvement in this machine is that it can be used to advantage for incline work, grading or crowning a roadway when necessary. The construction 30 of the machine, embodying as it does simple mechanical movements, allows of a complete and quick adjustment of all parts and ease of accessibility to all parts thereof.

The above and other objects and the novel 35 features of the machine will be apparent from the following description, taken in connection with the drawings, in which Figure 1 is a plan view of a machine embodying the invention; Fig. 2 is a side elevation of the 40 same; Fig. 3 is a view in outline showing two machines embodying my invention connected to a single leading device; Fig. 4 is an enlarged detail sectional view of one of the wheels of the machine, showing the manner 45 of mounting it; Figs. 5, 6 and 6^a are views of details; and Figs. 7 and 8 are, respectively, plan and cross sectional views of the manner of mounting caster wheels on the frame of the machine.

50 Referring to the drawings and Figs. 1 and 2 in particular, the frame A of the machine is built up of angle irons of suitable size, the side members of the frame consisting of two angle irons 10 and 11 spaced 55 apart a slight distance and having the open sides thereof facing inwardly and out-

wardly, respectively, whereby the vertical sides of the angle irons form supports for parts of the machine. At the front end the outside angle irons 11 are connected together at the bottom by a downwardly facing angle iron 12 and directly above the angle iron 12 there is another angle iron 13 located between the inner side angle irons 10 and bolted to the latter and to the bottom 6 angle iron 12. Two pairs of angle irons, similar to those at the front end of the machine, are located in spaced relation as at 14 and 15 near the rear end of the machine and are connected together intermediate their 7 ends by a transversely extending pair of spaced bars 16.

The frame A is carried by running gear which consists of two pairs of wheels 17 built up of three thicknesses 18 of board or other suitable material, as shown in Fig. 4. The boards 18 of proper thickness are cross-lapped and nailed or bolted together and then turned to a suitable diameter. Upon the rim of this wooden structure is placed 80 an iron or steel tire 19 which is fastened in any preferred manner. A hole 20 is bored through the center of the wooden structure large enough to receive a standard pipe nipple 21 projecting from the opposite sides of 85 the wheel and threaded at its outer ends. The pipe nipple 21 is of proper size to slip over the axle 22, allowing a close fit and the outer threaded ends thereof have pipe flanges 23 threaded thereon. Bolts 24 pass 90 through the clamps 23 and into the wooden wheel to clamp said flanges against the opposite sides thereof. A dowel pin 25 passes through an opening in the axle 22 and fits in recesses in one side of the wheel to key the 95 wheel on the shaft, the flange on that side of the wheel covering the recesses in which the pin 25 is located.

The axles 22 are divided at the center as indicated by the dotted line 221 and are 100 adapted to run in a sliding tube or sleeve 26 which extends between the inner hubs of the wheels on opposite sides of the frame. This arrangement permits each wheel to rotate independently of the other and on its own 105 axle. This feature permits the turning of the machine in a short space without undue friction or strain on the various parts.

In Figs. 7 and 8 I have illustrated another manner of permitting short turns in working over short sections of roadway and in close places. In that arrangement a caster

wheel 27 is mounted at each corner of the frame, supporting the latter by means of a bracket 28, the wheel being rotatably mounted in the lower end of said bracket. 5 A pin 29 is fastened at the upper end of the bracket and extends into a socket in the block 30, the outer end of the pin 29 projecting upwardly into the socket and having a cap 31 fitting thereon to retain the pin and bracket in place. 10

Referring to Fig. 4, the outer end of each axle 22 carries a standard pipe nipple 32 having on its inner surface a suitable Bab- bitt bearing or bushing 33. The nipple 32 15 constitutes the bearing for the axle and the opposite ends thereof are threaded to receive threaded standard pipe caps 34 and 35, respectively. The cap 34 closes the outer end of the bearing sleeve 32 and the cap 35 20 is bored to close-fit over the axle 22 and provides a chamber 36 therein opposite the inner end of the sleeve 32 for grease. The space around the opening between the cap 35 and axle 22 may be sealed with a suitable 25 packing 37 to exclude dust from the bearing. The inner cap 35 may thus act as a compression grease cup and together the caps will completely exclude dust from the bearing surfaces. 30

The axles are connected to the frame by means of U-bolts or clamps 38 which pass around the sleeves 32 and have the ends thereof projecting upwardly through the space between the side angle irons 10 and 11, the nuts 39 fitting the ends of the clamps 38 35 and holding them in position on the frame. By the construction of the wheels, their axles, and the manner of mounting them on the frame, these parts are readily accessible 40 for inspection and repair.

Between the front and rear walls of the machine the frame carries a plurality of reversible steel scraper blades 40. These blades are similarly constructed and mounted and therefore only one of them will be described. The blade 40 is curved trans- 45 versely and has a central longitudinal row of bolt holes 41 to receive bolts 42 by means of which it may be fastened to the spaced hangers 43. One of these hangers is shown 50 in Fig. 6 of the drawing and consists of a single casting provided with a part 44 curved to fit the rear side of the plate 40 and also having an elongated hole 45 to reg- 55 ister with one of the holes 41 to receive the bolt 42, whereby the blade 40 may be adjusted with reference to the hanger to take up the wear. The upper end of the hanger is provided with a square opening 46 adapt- 60 ed to fit the transversely extending bar 47 which supports all of the hangers. One side of the opening 46 in the upper end of the hanger is split as at 48 so that it may be sprung slightly to tightly clamp it to the 65 bar 47. The bar 47 has two collars 50 and

51 secured thereto and each of said collars is provided with spaced integral flanges 52. The spaced flanges 52 receive between them the lower ends of crank arms 53 and 54 hung by means of the U-shaped bearings 55 and 56 from the side frame members 10 and 11. The bearings 55 and 56 are clamped in the space between the frame members 10 and 11 and carry the horizontal parts of the crank arms 53 and 54. The bearing member 56 is 75 located in advance of the bearing member 55 whereby the blade 40 is hung so that it extends diagonally across the frame A.

The cranks 53 and 54 on opposite sides of the frame have knuckle or ball and socket joints at the upper ends thereof. As illustrated in Fig. 5, the upper end of the crank is curved so as to provide a ball 57 which will fit in a socket 58 formed by two complementary socket members 59 and 60 secured to the outer end of each of the links 61 and 62. The links 61 and 62 extend rearwardly and are connected to socket members 63 and 64, respectively, at the upper ends of the crank members of the next scraping 90 blade. The socket members 63 and 64 are double-ended and the other ends thereof are connected by reach rods 65 and 66 to suitable levers 67 and 68 which move over toothed segments 69 and 70 at the rear of the frame. By operating either the lever 67 or 68 the scraper blades may be raised or lowered on either side of the machine to adjust them to any inclination desired. In order to simultaneously raise both of the blades off of the ground, at both ends, one of the hangers 43 near the center of each blade is extended upwardly and made in the form shown in 6^a. The hanger of Fig. 6^a has an arm 711 which is provided at its upper end with a ball 712 which constitutes part of a ball and socket joint 71 similar to the ball and socket joints at the upper ends of the crank arms 53 and 54. The ball and socket joints at the upper ends of those hangers are connected together by a link 72 and a rod 73 is connected to the rear hanger. The rear end of the rod 73 is connected to a pivoted lever 74 which has parts adapted to engage the toothed segment 75 105 mounted on the plates 16.

When it is desired to couple two machines together to operate side by side over a road I use a leading gear L, as shown in Fig. 3 where the frames of the machines only are illustrated. The front cross bar of each frame comprises the lower and upper angle irons 12 and 13 and the vertical sides of these angle irons are located in front. Two angle plates are secured to the vertical sides of the angle irons 12 and 13 at the center of the frame and spaced apart a sufficient distance to provide a jaw 81 and the adjacent frame also is provided with a similar jaw 82 located at any suitable point at the front 120

end of the frame. The leading gear L is composed of angle irons and has two central bars 83 and 84 lying parallel to the frame and arranged with their flanges projecting upwardly and spaced apart to clamp between them the straps of iron 85 and 86. An angle iron 87 extends transversely of the bars 83 and 84 at the rear thereof and the outer ends of the angle iron 87 are connected to the front end of the leading gear by means of the angle braces 88 and 89. The straps 86 may be fastened between the side angle bars 10 and 11 of the frame and the outer ends of the angle iron 87 have straps 90 and 91 secured thereto and fastened respectively to the jaws 81 and 82. By this arrangement the draft applied to the front end of the leading gear L will be distributed to the two machines at the rear. In order to hold the machines a definite distance apart lugs 92 are bolted to one side of one machine and lugs 93 are bolted to the immediately adjacent side of the other machine. One of the machines is run a little in advance of the other machine and suitable bolts 94 are passed through holes in the ends of the lugs 92 and 93.

The operation of the machine will be apparent from the foregoing description. The levers 67 and 68 at the rear of the machine may be operated to simultaneously raise the scraping blades at either side of the machine and the lever 74 at the center is designed for the purpose of bodily raising the blades at a single operation when the machine is inoperative or in passing over obstructions or for any purpose, when said blades are desired to be lifted without having to handle both the adjusting levers 67 and 68. The hangers which are controlled by the lever 74 are also designed to hold the blades at any desired angle while the machine is at work. The hangers of the machine are provided with vertical slots to allow for shifting the blades to take up wear or for making any desired adjustment.

It will be seen that the wheels are located entirely within the marginal outline of the frame and the blades extend beyond the sides of the frame.

While I have shown and described the invention in detail I do not wish to be limited to the exact construction illustrated.

Having thus described the invention, what is claimed and desired to be secured by Letters is:

1. In a road building machine, the combination of a supporting frame, running gear therefor, a blade extending transversely of the machine, and means for supporting said blade comprising cranks pivotally carried by said frame, a bar supported by said cranks, and rigid hanger arms carried by said bar and attached to said blade.
2. In a road building machine, the combination of a supporting frame, running gear therefor, a blade extending transversely of the machine, means for supporting said blade comprising cranks pivotally carried by said frame, a bar extending longitudinally of the blade and pivoted at the ends of said rigid arms of said cranks, and rigid hanger arms depending from said bar and attached to said blade, and means for rocking said cranks to raise and lower said blade.

3. In a road building machine, the combination of a supporting frame, running gear therefor, a blade extending transversely of the machine, means for supporting said blade comprising cranks pivotally carried by said frame, a bar extending longitudinally of the blade and rotatably supported by said cranks and hangers depending from said bar and attached to said blade, and rigidly connecting the bar and blade together, means whereby either of said cranks may be rocked to raise or lower either end of said blade, and means between said cranks whereby said blade may be simultaneously raised or lowered at both ends.

4. In a road building machine, the combination of a supporting frame, running gear therefor, blades extending transversely of the machine, and means for supporting said blades comprising pairs of cranks carried by said frame, a bar carried by each pair of cranks, hangers carried by each bar and attached to a blade, and means for simultaneously rocking the cranks on either side of said frame to raise or lower the ends of the blades at will.

5. In a machine of the class described, the combination of a supporting frame, running gear therefor, a scraper blade extending transversely of the machine, cranks pivotally mounted on said frame, a bar pivotally mounted in said cranks, means whereby the blade is connected to said bar, means for rocking the cranks to raise or lower the bar and blade, and means for rocking the bar in its bearing in said cranks to raise and lower the blade independent of said cranks.

6. In a road building machine, the combination of a supporting frame, running gear therefor, a blade extending transversely of the machine, means for supporting said blade comprising cranks carried by said frame, a bar pivotally supported at the lower ends of said cranks, and hangers rigidly mounted on said bar and attached to said blade, means for rocking said cranks to raise and lower said blade, said rocking means comprising rods terminating in levers, and knuckle joints connecting said rods to said cranks.

7. In a road scraping machine, the combination of a supporting frame, running gear therefor, a scraper blade extending transversely of the machine, cranks pivoted

- on said frame and provided with bearings, a bar extending transversely of the frame above the blade and mounted in the bearings in said cranks, hangers rigidly attached to 5 said bar and to said blade for supporting the blade from the bar, means for operating the cranks to raise and lower said bar and the blade attached thereto, an arm rigidly attached to said bar, and an operating rod 10 connected to said arm for rocking the bar in said bearings in the cranks to change the inclination of the blade to the ground.
8. In a road building machine, the combination of a supporting frame, running gear therefor, an elongated double-edged transversely curved blade extending diagonally beneath the frame, and means for supporting said blade from the frame comprising spaced hangers having vertical slots therein, 15 bolts passing through said slots in the hangers, and through holes located substantially on the longitudinal center line of said blade, whereby said blade may be adjusted vertically to take up wear and may also be reversed to present a different working edge.
9. In a road building machine, the combination of a supporting frame, running gear therefor, a blade extending transversely beneath the frame, means for supporting said 20 blade comprising cranks hung on said frame, a bar pivotally connected to said cranks, and hangers fixed on said bar and attached to the rear side of said blade, means for rocking said cranks comprising levers connected to 25 the cranks by knuckle joints, and means for turning said bar independently of said cranks to bodily raise and lower said blade.
10. In a road building machine, the combination of a supporting frame, running gear therefor, a blade extending transversely beneath the frame, means for supporting said blade comprising cranks hung on said frame, a bar pivotally supported by said cranks, and hangers fixed on said bar and attached 30 to the rear side of said blade, means for rocking said cranks comprising levers connected to the cranks by knuckle joints, one of said hangers having an upwardly extending part and a lever connected to said upwardly extending part by a knuckle joint and adapted to turn said bar independently of said cranks to bodily raise and lower said blade.
11. In a road building machine, a frame comprising side members made up of parallel angle irons having their vertical flanges spaced apart, road scraping means mounted on said frame and U-shaped hangers depending from said frame and extending through the space between said flanges, axles 35 mounted on said hangers, and wheels carried by said axles.
12. In a road building machine, the combination of a supporting frame comprising side members built up of parallel angle irons having their vertical flanges spaced 40 apart, road scraping members depending from said side members of the frame, hangers extending through the spaces between said flanges and depending from the under side of said frame, divided axles beneath said frame, a wheel on each part of an axle, and bearings at the outer ends of the axles and fitting in the depending parts of the hangers on said frame. 70
13. In a road building machine, the combination of a supporting frame comprising sides built up of parallel members spaced apart, hangers extending through the spaces between said parallel members and depending from the under side of the frame, cranks pivoted in said hangers, a scraper blade connected to said cranks and extending across the frame, and means for rocking said cranks to raise and lower said scraper blade, said hangers being adjustable longitudinally 80 of the sides of the frame to change the angularity of the scraper blade. 85
14. In a road building machine, the combination of a supporting frame, running gear therefor, a blade extending transversely of the machine, means for supporting said blade comprising cranks pivoted on said frame, a bar extending transversely of the frame and rotatably supported by bearings in said cranks, means for connecting said blade to said bar in its bearings in said cranks, and means for turning said bar to simultaneously raise or lower the blade at both ends. 90
15. In a road building machine, a leading gear comprising a substantially V-shaped frame having means at opposite sides and the center whereby it may be connected to a plurality of road building machines the connecting means at one side of said frame 95 being longer than that at the opposite side whereby one of the machines drawn thereby will be disposed in advance of the other machine. 100
16. In a machine of the class described, the combination of a supporting frame, running gear therefor, a scraper blade extending transversely of the frame, crank attaching means rigidly mounted on said blade and movable bodily therewith, cranks 110 carried by said frame, each crank having a rigid arm, said crank attaching means on the blade being pivotally mounted in the ends of the rigid arms of said cranks, and means whereby said cranks may be operated 115 independently of one another to raise or lower the ends of the scraper blade. 120
17. The combination of two road building machines, each machine comprising a blade extending diagonally across the machine, the machines being arranged side by side with the rearmost part of the blade on one machine in advance of the blade on the other machine, and having their immediately adjacent sides provided with lugs, pins ex- 125 130

tending through the lugs to maintain the machines a fixed distance apart, means at the forward ends of the machines whereby a leading gear may be attached thereto, and 5 a leading gear having means at the rear end thereof attachable to said machines whereby both machines may be drawn by a single draft device.

18. In a road building machine, the combination of a supporting frame, running gear therefor, a double-edged blade extending transversely of the machine beneath the

frame, means for supporting said blade comprising a bar pivotally supported by said frame, rigid hanger arms carried by 15 said bar, means for adjustably securing said blade to said hanger arms whereby the blade may be reversed to use either longitudinal edge thereof as a working edge, and means for turning said bar on its pivotal support 20 to raise and lower the blade.

In testimony whereof I affix my signature.

HARRY N. HALL.
